(57) **CLAIM**

The ornamental design for a magnetic toy set, as shown and described.

DESCRIPTION

FIG. 1 is a front and bottom perspective view of a magnetic toy set;

FIG. 2 is a rear and top perspective view of the magnetic toy set;

FIG. 3 is a front and bottom perspective view of a first piece of the magnetic toy set;

FIG. 4 is a rear and top perspective view thereof;

FIG. 5 is a front elevation view thereof;

FIG. 6 is a rear elevation view thereof;

FIG. 7 is a left side elevation view thereof, and a right side elevation view thereof is a mirror image of the left side elevation view;

FIG. 8 is a top plan view thereof, and a bottom plan view thereof is a mirror image of the top plan view;

FIG. 9 is a front and bottom perspective view of a second piece of the magnetic toy set;

FIG. 10 is a rear and top perspective view thereof;

FIG. 11 is a front elevation view thereof;

FIG. 12 is a rear elevation view thereof;

FIG. 13 is a left side elevation view thereof, and a right side elevation view thereof is a mirror image of the left side elevation view;

FIG. 14 is a top plan view thereof, and a bottom plan view thereof is a mirror image of the top plan view;

FIG. 15 is a front and bottom perspective view of a third piece of the magnetic toy set;

FIG. 16 is a rear and top perspective view thereof;

FIG. 17 is a front elevation view thereof;

FIG. 18 is a rear elevation view thereof;

(Continued)

FIG. 19 is a left side elevation view thereof, and a right side elevation view thereof is a mirror image of the left side elevation view;
 FIG. 20 is a top plan view thereof;
 FIG. 21 is a bottom plan view thereof;
 FIG. 22 is a front and bottom perspective view of a fourth piece of the magnetic toy set;
 FIG. 23 is a rear and top perspective view thereof;
 FIG. 24 is a front elevation view thereof;
 FIG. 25 is a rear elevation view thereof;
 FIG. 26 is a left side elevation view thereof, and a right side elevation view thereof is a mirror image of the left side elevation view;
 FIG. 27 is a top plan view thereof, and a bottom plan view thereof is a mirror image of the top plan view;
 FIG. 28 is a front and bottom perspective view of a fifth piece of the magnetic toy set;
 FIG. 29 is a rear and top perspective view thereof;
 FIG. 30 is a front elevation view thereof;
 FIG. 31 is a rear elevation view thereof;
 FIG. 32 is a left side elevation view thereof;
 FIG. 33 is a right side elevation view thereof;
 FIG. 34 is a top plan view thereof;
 FIG. 35 is a bottom plan view thereof;
 FIG. 36 is a front and bottom perspective view of a sixth piece of the magnetic toy set;
 FIG. 37 is a rear and top perspective view thereof;
 FIG. 38 is a front elevation view thereof;
 FIG. 39 is a rear elevation view thereof;
 FIG. 40 is a left side elevation view thereof, and a right side elevation view thereof is a mirror image of the left side elevation view;
 FIG. 41 is a top plan view thereof; and,
 FIG. 42 is a bottom plan view thereof.
 The broken lines in the figures illustrate portions of the magnetic toy set that form no part of the claimed design.
